UNITED STATES PATENT OFFICE.

AVERY M. TRUESDALE AND ERNIE A. THOMPSON, OF JEFFERSON, OHIO.

CURTAIN AND SHADE BRACKET.

No. 872,862.

Specification of Letters Patent.

Patented Dec. 3, 1907.

Application filed April 24, 1907. Serial No. 370,059.

To all whom it may concern:

Be it known that we, AVERY M. TRUESDALE and ERNIE A. THOMPSON, citizens of the United States, residing at Jefferson, in the county of Ashtabula and State of Ohio, have invented new and useful Improvements in Curtain and Shade Brackets, of which the following is a specification.

This invention relates to a curtain and shade holder of that type comprising a pair of brackets that are adapted to be applied independently to the window casing so that they can be used in connection with windows of different widths.

15 The invention has for one of its objects to improve and simplify the construction of devices of this character so as to be comparatively easy and inexpensive to manufacture, of substantial design and readily applied.

20 A further object of the invention is the provision of combined shade and curtain brackets each comprising an integral structure and having a screw cast or otherwise suitably secured to the shank or body thereof so that the brackets can be readily applied in the desired position on the window frame without the use of special tools and in a simple and convenient manner.

25 A still further object is to provide a pair of brackets having upwardly extending arms that are curved laterally and upwardly from the shank portions so that the curtain can be accommodated between the arms on the curtain rod that is supported upon the extremity of the arms and thus permit the curtain to be of greater width than the shade which is essential for the attractive appearance of the window draped with a curtain.

30 With these objects in view and others as will appear as the description proceeds, the invention comprises the various novel features of construction and arrangement of parts which will be more fully described hereinafter and set forth with particularity 45 in the claims appended hereto.

35 In the accompanying drawings which illustrate one of the embodiments of the invention, Figure 1 is a front elevation of the upper portion of a window frame showing the improved brackets applied thereto. Fig. 2 is a side view of one of the brackets. Fig. 3 is a plan view thereof.

40 Similar reference characters are employed to designate corresponding parts through the 55 views.

Referring to the drawing, 1 designates a

window frame to which the brackets 2 are applied. These brackets are made in pairs and in the form of rights and lefts. Each bracket is an integral casting or other structure comprising a shank or body portion 3 that has a circular base 4 and a screw 5 cast or otherwise suitably secured in the base and extending outwardly from the shank 3 is an arm 6 that curves upwardly and laterally and terminates in an eye 7. The brackets 2 are secured to the window casing by means of the screws 5 and the arms 6 are arranged to extend outwardly from the opening of the window frame or in other words, the body portions of the brackets are nearer together than the eyes or extremities of the arms. The body portions are each provided with a plurality of spaced recesses 8 for the reception of the pintles 9 of a shade roll 10 which latter may be of any approved design. The brackets are so located that the shade will be confined between the vertical members of window frame according to the usual custom. In the eyes 7 is arranged a curtain rod 11 of ordinary form for supporting a curtain and since the distance between the brackets at the terminal portions is considerably greater than the distance between the shanks of the bracket, the curtain can be stretched considerably wider than the shade so that the curtain will cover not only the shade but a portion of the window frame, thus adding to the appearance of the window and furthermore, the curtain will be hung from a point somewhat above the shade. Since the fastening screws are rigidly secured to the brackets, the latter can be quickly and conveniently secured in place by using the bracket itself as a handle or driver, thus enabling any one to secure the brackets without the aid of tools. The brackets are of substantial construction and neat in appearance and cover so little of the window frame that they do not have to be taken down in repainting the window frame.

45 From the foregoing description taken in connection with the accompanying drawing, the advantages of the construction will be readily understood and while we have described the principle of operation of the invention together with the device which we now consider to be the best embodiment thereof, we desire to have it understood that the device shown is merely illustrative and that such changes may be made when desired as are within the scope of the claims.

Having thus described the invention, what we claim as new is:—

1. A bracket having a combined curtain and shade supporter comprising a shank having recesses in one of its side surfaces extending partially through the same, a screw rigidly secured to one end of the shank, an outwardly extending arm integrally connected with the shank at the opposite end and curving upwardly and laterally therefrom and provided with an eye at its extremity.
2. A bracket comprising a shank having recesses in one of its side surfaces and suitably spaced apart, a fastening device rigidly secured to one end of the shank, an outwardly extending arm curved laterally and upwardly so as to be horizontally and vertically out of the plane of the shank and parallel therewith, the said shank forming a head to permit the fastening to be driven into a support.

In testimony whereof, we affix our signatures in presence of two witnesses.

AVERY M. TRUESDALE.
ERNIE A. THOMPSON.
